PLASTIC FIGURED TEXTILE FABRIC

Jerome F. Kelly, Brooklyn, and Robert A. Poisson, New York, N.Y., assignors to Riegel Textile Corporation, a corporation of Delaware

Filed July 28, 1958, Ser. No. 51,957

Term of patent 14 years

(Cl. D87—3)

Fig. 2

FIG. 1 is a plan view of a representative portion of a plastic figured textile fabric incorporating our new design, the repeating pattern of the design being indicated by solid lines, and

FIG. 2 is an enlarged sectional detail taken substantially on the line 2—2 in FIG. 1.

We claim:

The ornamental design for a plastic figured textile fabric, as shown and described.
